UNITED STATES PATENT OFFICE.

EDWARD E. WILLARD, OF RIDGWAY, PENNSYLVANIA.

SAWMILL AND PLANER.

SPECIFICATION forming part of Letters Patent No. 700,870, dated May 27, 1902.

Application filed July 2, 1897. Serial No. 643,274. (No model.)

To all whom it may concern:

Be it known that I, EDWARD E. WILLARD, a citizen of the United States, residing at Ridgway, in the county of Elk and State of Pennsylvania, have invented a new and Improved 5 Rotary Log-Clamp, of which the following is a specification.

My invention relates to machines for cutting boards from logs by means of circular 10 saws carried on mandrels rotating at right angles and so adjusted that logs firmly held by the clamps and moved on a reciprocating carriage past the saws may have cut from their outer parts boards of a uniform size and cut 15 nearly or quite radially, such boards being especially valuable for use in the construction of floors.

Referring to the different illustrations, Figures 1, 2, 3, 4, 5, 6, and 12 show the construction 20 of the clamps intended for use in cutting boards from whole logs. Figs. 7, 8, 9, 10, and 11 show the slightly-different construction required in order to adapt the clamps for use in cutting boards from logs which have been previously 25 divided into halves by passing a saw longitudinally through their centers.

In the several drawings, A represents a platform or carriage supported on the wheels A', on which are mounted the guide-bars F² F³, 30 which pass through and keep in position the cross-heads G G' G² G³ G⁴ G⁵ G⁶, which support the clamps O O' O² O³ O⁴. The guide-bars F² F³ extend above the cross-heads and pass through the plate T and are finally secured by the nuts N N. As shown in Fig. 4, the cross-heads may be moved up or down on the guide-bars by means of the hand-wheel I², actuating the screw-shaft H², which also passes through the plate T. The clamps pass through 40 and are journaled to rotate in the part of the cross-head extending outside of the guide-bars and over the circular saws, and the log being supported between two of the clamps is in this manner presented to the saws at the proper 45 height and position for severing the boards. As shown in Figs. 1 and 3, one end of the log may be supported by the clamp O⁴, while the other end rotates on the center V, or, as shown in Figs. 5 and 6, the log may be supported by 50 the clamp O⁴ and disk Q².

Figs. 1 and 5 are front views, and Fig. 2 is a top view, of a clamp, in which O⁴ is a cylind-

rical part passing through the cross-head G⁵ and journaled to rotate therein. The inner end of O⁴ is made in the form of a flange having upon one of its sides suitable teeth for the support of one end of a log, while the other side of the flange presents a considerable surface intended to press against the side face of the cross-head when the log is pressed against the teeth upon the opposite side of the flange. O⁴ extends a short distance outside of the cross-head, as shown more fully in Fig. 12, and is fitted to enter and slide in a shallow recess formed in the washer S'. Through the center of O⁴ is a threaded hole in which the clamp-screw R² works, actuated by the hand-wheel K⁶ at its outer end. The screw-shaft R² passes through a hole in the center of the washer S', in which it freely rotates and at the same time holds the washer in its proper position with the aid of a collar formed on the screw-shaft and designed to press against the washer and force it against the outside face of the cross-head. When the screw R² is rotated in the proper direction, the result is to draw the washer S' and flange O⁴ toward each other, producing a pressure against the faces of the cross-head sufficient to prevent O⁴ from rotating when so desired, and the log, having the teeth on the flange O⁴ pressed into it, is also prevented from rotating.

Fig. 6 shows a clamp of somewhat-different construction. In this G³ is a cross-head, through which is a hole in which the cylindrical part O³ is fitted to rotate, the set-screw E³ preventing it from rotating when so desired. O³ is provided with a flange on each side of G³, holding the parts in place. One of the flanges, as shown in Fig. 11, may be removable, being held in place by screws. Through the center of O³ is a threaded hole to receive the screw P², as more clearly shown in Fig. 12. The hand-wheel K² is firmly attached to the outer end of the screw-shaft P², and near its inner end is formed a collar designed to press against the disk Q' when the screw is rotated in the proper direction. The disk Q' is loosely attached to the inner end of the screw P² in such a manner that the screw may rotate without carrying the disk around with it, one way in which the disk may be so attached being shown in Fig. 11, where the screw P passes through a hole in the center

of the disk and is kept in place by the pin d , driven through the screw, the ends of the pin projecting beyond the screw a sufficient distance to prevent the withdrawal of the screw 5 from the disk. On the inside of the disk Q' are a number of teeth, which are pressed into the end of the log when the collar on the screw P^2 is pressed against the opposite side of the disk, thus forming a support for that end of 10 the log.

When intended for sawing half-logs, the construction of the clamp is as shown in Fig. 7, in which L represents a clamp-bar extending the entire length of the half-log and 15 which passing through the toothed disk Q is firmly attached to the journaled clamps O and O' . The clamp-bar L is placed entirely to one side of the centers of O and O' , so that their common axis of rotation is along the 20 middle of one of the sides of the clamp-bar, and for that reason the screw P passes through the journaled cylinder O and is attached loosely to the toothed disk Q a sufficient distance to one side of their centers to clear the 25 bar L , along which the disk Q slides when the screw P is rotated, as is more clearly shown in Figs. 8, 9, 10, and 11. The construction of O and O' and of the parts connected with them is in other respects as shown in Figs. 30 5 and 6 and as already described when referring to those figures. In operation the half-log is placed against the clamp-bar L , Fig. 7, between the toothed disk Q and the toothed flange of the clamp O' , with the middle of the 35 sawed side exactly in line with the clamp-screw R and nearly in line with the clamp-screw P . To prevent the journaled clamp O from rotating, the set-screw E is screwed in against it. The disk Q is then pressed forward by rotating the clamp-screw P until the teeth on the disk Q are pressed against and into the end of the half-log, and the rotation of P being continued the half-log is caused to 40 slide along the clamp-bar L and is pressed against the teeth on the clamp O' until they, as well as the teeth on the disk Q , have been forced into the two ends of the half-log sufficiently to secure and support the half-log in place. The journaled clamp O is now made 45 free to rotate by slightly withdrawing the set-screw E , and the half-log having been moved up or down, as desired, by means of the screws $H H'$, is rotated until it reaches the proper position to suit the saws, at which 50 point it is made fast by means of the screw R , which firmly clamps and holds it in that position while the saws are passing through it. The saws are not shown in the drawings. Two or more of them are adjusted to cut vertical 55 kerfs nearly or quite in direction toward the heart of the log, thus forming the radial sides of the boards, while two other saws cut kerfs at right angles to them, thus forming the edges of the boards.

60 65 When in use for sawing whole logs, the operation is in all respects as described for the sawing of half-logs, except that the center of the

log is placed in line with the centers of the supporting-clamps.

The mechanism thus described and which I claim as new, and desire to secure by Letters Patent, is as follows:

1. A rotary log-clamp consisting of a cylinder journaled to rotate in a suitable bearing, a flange formed on or firmly attached to the inner end of the cylinder and provided with teeth designed to secure and sustain one end of a log when it is pressed against them, while the other end of the log is supported by any suitable center on which it may rotate, and so constructed that the log may at the same time be pressed and firmly held against the toothed flange of the cylinder; at the outer end of the journaled cylinder a washer recessed to receive the projecting end of the cylinder and having a hole in its center through which passes the shaft of a clamp-screw which is fitted to work in a threaded hole extending through the cylinder, the screw-shaft being provided with a collar formed on or firmly attached to the shaft outside of the washer, and designed to press against the washer and draw it toward the cylinder, in the manner and for the purpose described.

2. A rotary log-clamp consisting of a flanged cylinder journaled to rotate in a suitable bearing, a threaded hole in the cylinder through which a clamp-screw with a corresponding thread passes; the screw having journaled to its inner end a disk provided with teeth which may, by rotating the screw, be pressed firmly against and into one end of a log to secure and sustain it, while the other end is supported by any suitable center on which it may rotate, and by which it may be pressed and held against the teeth of the disk; a set-screw being fitted to press against the journaled cylinder to prevent it from rotating when so desired, as shown and described.

3. A rotary log-clamp consisting of a flanged cylinder journaled to rotate in a suitable bearing, a threaded hole in the center of the cylinder through which a clamp-screw with a corresponding thread passes and works, the clamp-screw rotated by means of a hand-wheel attached to its outer end and having journaled to its inner end a disk provided with strong teeth which may, by rotating the screw, be pressed firmly against and into the end of a log, a set-screw passing through a threaded hole in the bearing and pressing against the cylinder to prevent the cylinder from rotating when so desired; and co-operatively and in combination with the same, another rotary log-clamp consisting of a cylinder journaled to rotate in a suitable bearing, a flange formed on, or firmly attached to, the inner end of the cylinder and provided with teeth designed to secure and sustain one end of a log when it is pressed against them; at the outer end of the cylinder, a washer recessed and constructed to slide a short distance along the journaled part, a hole through its center in which a clamp-screw freely rotates and retains it in

place: the journaled cylinder having a threaded hole through its center in which the clamp-screw, actuated by a hand-wheel at its outer end and provided with a corresponding thread, 5 passes and works: the clamp-screw also provided with a collar firmly attached and designed to press against the washer and draw it toward the cylinder when the clamp-screw is rotated and in this manner to clamp the 10 cylinder and prevent it from rotating when so desired, substantially as shown and described.

4. A rotary log-clamp consisting of a longitudinal bar having firmly fastened near its 15 ends flanged cylinders fitted to bearings in which they may freely rotate: at the outer end of one of the cylinders a washer, recessed and constructed to slide a short distance along

the journaled part, a hole through its center in which a clamp-screw freely rotates, the 20 screw working in a threaded hole through the center of the cylinder to draw the washer toward the cylinder and prevent the cylinder from rotating when so desired: a threaded hole through the other journaled cylinder in 25 which a clamp-screw works having a disk at its inner end in which it is journaled to rotate, the disk having a hole through which the longitudinal bar is passed on which it slides when the screw is rotated, substantially as 30 shown and described.
